UNITED STATES PATENT OFFICE.

GEORGE C. REESE, OF DARBY, PENNSYLVANIA.

INTERNAL-COMBUSTION ENGINE.

1,191,827.

Specification of Letters Patent. Patented July 18, 1916.

Application filed November 26, 1915. Serial No. 63,613.

To all whom it may concern:

Be it known that I, GEORGE C. REESE, a citizen of the United States, residing in Darby, Delaware county, State of Pennsylvania, have invented an Internal-Combustion Engine, of which the following is a specification.

While it is recognized that engines of the two cycle type are considerably cheaper to build as well as simpler to operate than those of the four cycle type, they are not fitted for many classes of work owing to their low power and efficiency resulting from their slow speed.

One object therefore of my invention is to provide an internal combustion engine of either the two or four cycle type whose construction shall be such that it will be possible for it to operate at materially higher speeds than are now allowable for engines of the same piston displacement and at the same time with a relatively high efficiency.

More particularly the invention contemplates the provision of an internal combustion engine with means whereby the speed of its piston shall be materially decreased at certain parts of its stroke and correspondingly increased at other parts, in order to permit of the proper exhaust of the products of combustion and the intake of a sufficient fuel charge while reducing the time in which heat may be radiated from the hot gases of the exploded charge to the piston, cylinder, water jacket, etc.

These objects and other advantageous ends I secure as hereinafter set forth, reference being had to the accompanying drawings, in which,

Figures 1 and 2 are elevations partly in section and to some extent diagrammatic illustrating a two cycle engine equipped with my invention; and Fig. 3 is an elevation partly in section illustrating the invention as applied to an engine of the four cycle type.

In the above drawings 1 represents the cylinder and 2 the crank case of a two cycle engine having a piston 3 connected by a rod 4 with a crank shaft 5 in the well known manner. According to my invention I provide an auxiliary or counter shaft 6 parallel with the crank shaft 5 and on it mount a fly wheel 7, connecting said two shafts by gears 8 and 9. Said gears are primarily eccentrically mounted, being preferably

elliptical in outline and in both cases the center lines of the shafts 5 and 6 pass respectively through one of the principal foci of the gear which is mounted upon it. 60 Moreover the gear 8 is so set on the shaft 5 that when the piston 3 is at the upper end of its stroke it is engaged by those teeth of the gear 9 farthest from the shaft 6 and at a minimum distance from said shaft 5. 65

Obviously after such an engine has been brought up to speed, the explosion of a charge in its cylinder will force its piston down at a maximum speed and transmit power through the shaft to the machine to be driven, a certain portion of said power being stored by the fly-wheel. When said piston reaches the end of its stroke and uncovers the exhaust port, it is permitted to move at a lower rate even though the shaft 75 6 under the action of the fly wheel tends to continue its revolution at a uniform speed, the gear 9 on the shaft 6 driving the gear 8 on the shaft 5 at a reduced speed owing to the elliptical construction illustrated. The 80 same condition exists after the exhaust of the products of combustion has occurred and the fuel inlet port 11 has been opened, although the speed of the piston is gradually increased during the compression stroke 85 until, when the charge is exploded, it is again forced downward at a speed which causes revolution of the shaft 5 at a higher rate than that of the shaft 6. As a result of this operation the time in which it is possible for the highly heated gases of explosion to radiate heat to the cylinder, piston, water jacket, etc., is materially reduced, while the time allowed for the exhaust of spent gases and intake of fuel is correspondingly increased. 90

It is therefore permissible for the engine to be operated at an average speed which is considerably greater than would otherwise be economically possible in a two cycle engine, and at the same 100 time, with the same piston displacement an engine equipped with my invention would operate at a materially higher efficiency because of the reduced loss of heat during the expansion of the hot gases. By the invention above described it is thus possible for a two cycle engine to be employed for work where its slow speed and poor efficiency have hitherto prohibited such use.

If desired my invention may be applied to engines of the four cycle type by providing a counter shaft 13 and a pair of coact-

ing eccentrically mounted gears 14 and 15 as illustrated in Fig. 3;—one of said gears being mounted on the crank shaft 16 and the other on said counter shaft which also 5 carries the fly wheel 17. The gears 14 and 15 are so set in this instance that the speed of the crank shaft 10 is higher than that of the counter-shaft 13 on the firing and intake strokes but is less than that of said shaft on 10 the compression and exhaust strokes. As before, owing to the increased piston speed during the firing stroke, less time is permitted for the radiation of heat from the hot gases to the cylinder, piston, etc., so that 15 a higher efficiency of operation is secured. At the same time owing to the reduction of speed of the piston during its compression and exhaust strokes, the engine may be operated without loss of efficiency at higher 20 speeds than have hitherto been allowable.

In both the two cycle and four cycle types of engine employing my invention it will be understood that the fly wheel on the counter shaft retains the latter and the apparatus 25 driven therefrom at a substantially constant speed while the crank shaft and the parts attached thereto are caused to operate at a speed which varies during each stroke as above indicated. While I have illustrated 30 my invention as applied to a single cylinder engine, it is obviously immaterial whether said engine be equipped with two or more cylinders since the counter shaft with its fly wheel and the gears connecting 35 with the crank shaft perform the same function in any case.

As will be understood by those skilled in the art, the setting of the gears 8 and 9 is not necessarily limited to the relative positions shown in the drawings, since it is conceivable that it may be advantageous to have the variations in speed of the two shafts 5 and 6 occur at points in the cycle in the engine other than those above described. It 45 will further be understood that when the main shaft 6 is to be driven by power from a number of cylinders, these may be grouped around it in any manner best suited to economize space or secure any other desired result, without departing from my invention.

the crank shafts being connected to said main shaft through gears as above described.

I claim:—

1. The combination in an internal combustion engine of a crank shaft; a counter shaft; means tending to maintain the speed of the counter shaft substantially uniform; and means connecting said shafts for causing the speed of the crank shaft to vary during each stroke. 55

2. The combination with an internal combustion engine having a crank shaft of a counter shaft; a fly wheel on said counter shaft; and means connecting the crank shaft 65 and counter shaft for causing variation of the speed of the former while allowing the latter shaft to rotate at a substantially uniform speed.

3. The combination with an internal combustion engine having a crank shaft of a counter shaft; elliptical gearing connecting said shafts; and a fly wheel on the counter shaft. 70

4. The combination with an internal combustion engine having a crank shaft of a counter shaft; eccentrically mounted gears connecting said shafts; and a fly wheel on the counter shaft. 75

5. The combination with an internal combustion engine having a crank shaft of a counter shaft; a fly wheel on the counter shaft; with eccentrically mounted gears connected between said shafts and set to cause a retardation of the piston speed during the exhaust of the products of combustion. 80

6. The combination with a two cycle internal combustion engine having a crank shaft of a counter shaft; a fly wheel on the counter shaft; with gearing connecting said shafts mounted to permit rotation of the crank shaft at a higher speed than the counter shaft during the firing stroke of the piston, and to allow said crank shaft to move at a speed lower than that of the counter shaft during the exhaust and intake. 90

GEORGE C. REESE.
